UNITED STATES PATENT OFFICE

ARTHUR L. GOLDENSTAR, OF DULUTH, MINNESOTA

FENCE POST ANCHOR

Application filed September 19, 1928. Serial No. 307,021.

This invention relates to anchoring devices and the like and is illustrated herein as embodied in a device for use in connection with fence posts, tent poles, and other similar objects, to prevent them from becoming accidentally displaced after once being embedded in the earth.

Many devices have heretofore been devised for performing the function recited above, but generally the use of the devices of the prior art involves the formation of a plurality of holes, one of which is adapted to receive the base of the pole, or post, and the other, the anchoring device. In view of the fact that the digging of these holes is laborious and involves a considerable expenditure of time, it will be appreciated that the provision of an anchoring device which would eliminate the necessity of providing a separate hole for its embedment would be extremely desirable, and it is accordingly an important object of the present invention to provide a device of this improved character that is extremely simple in design and construction and efficient in operation.

A feature of the invention that lends itself to the accomplishment of the recited object consists in providing the base of a fence post, or the like, with an elongated anchoring member adapted to project laterally beyond the sides of the post to engage within the surrounding earth. In the illustrated embodiment of the invention, the elongated anchoring member comprises a flat plate which is secured, in perpendicular relation, to the base extremity of the post. In setting up a fence post equipped with an anchor of the new style, it is contemplated to dig a hole of an elongated cross-sectional shape, to accommodate readily the elongated anchoring member, and thereafter, when the post has been seated in the hole, to rotate the post a quarter of a turn in either direction to cause the laterally projecting ends of the plate to embed themselves in the undisturbed soil at the sides and bottom of the hole. Thus the anchor receives its holding power not only from the earth which is tamped in the hole, but also in a large degree from the grip it

takes in the natural undisturbed soil at the sides and bottom of the hole.

To facilitate the cutting of the anchoring plate into the earth during rotation of the post to which the plate is attached, the invention contemplates forming the plate of such a shape that a slicing or shearing action takes place, as contrasted with a pushing action, and as illustrated, the plate is made of rectangular form with its corners cut away uniformly to provide angularly disposed edges which slice their way into the soil as already mentioned. To insure that the anchoring plate will remain bodily stationary at the bottom of hole during rotation thereof, and to insure against it tilting or otherwise becoming displaced bodily—in which condition the post will lean and no longer be disposed in the desired line of the fence—a further feature of the invention consists in forming the elongated plate symmetrically with respect to a center line whereby equal pressure is exerted upon the diagonally opposite edges during the cutting operation and the post tends to remain vertical in the hole.

Still another feature of the invention consists in the provision of inexpensive and efficient means for securing the anchor to the post. As illustrated, bolts extend between the anchor and the post rigidly to connect the two members in such a manner that the likelihood of breakage that arises from the use of moving parts, such as hinges, pivots, etc., is reduced to a minimum. Furthermore, such a provision permits rotation of the fence post in either direction which is very important inasmuch as obstructions are often encountered during rotation of the post in one direction that make it desirable to rotate the post in the opposite direction.

Other objects and features of the invention will become apparent from a reading of the following specification in the light of the accompanying drawing, in which—

Figure 1 is a plan view of a hole having a post provided with the improved anchoring device disposed therein;

Figure 2 is a fragmentary view showing the disposition of the lower portion of the post

within the hole before the anchoring device has been put in operation;

Figure 3 is a view similar to Figure 1 showing the anchoring device in an operative position;

Figure 4 is a view similar to Figure 2 showing the anchoring device in an operative position; and

Figure 5 is a view showing the manner in which the post is braced.

As shown in the drawing, the reference numeral 10 indicates a fence post of a conventional type that is made from a metal angle iron, or bar, as more clearly shown in Figure 1. A post of this character can be conveniently set into the ground by boring one or more auger holes and inserting the post within the bored out hole. A hole so formed is more desirable than a dug hole inasmuch as considerably more earth must be removed in making a hole of the latter type, and, in replacing the earth after the post has been inserted, the back-filled earth cannot be tamped as solidly in the large conically shaped dug hole as in a smaller cylindrical hole of the type that is made by an auger.

For the purpose of preventing the fence post from becoming dislodged or pulling out during use, it is provided with an anchoring device shown in the form of a flat elongated member 12 which is connected rigidly to the lower extremity of the fence post 10 by means of standard bolts 14 that are bent, as shown in Figures 2 and 4, to extend outwardly from the post and thence downwardly through the anchoring member 12. While the connecting means has been illustrated herein in the form of standard bolts, it is, of course, to be understood that various other suitable fastening means, as for example, rivets, clamps, etc., may be employed if desired.

In the use of a post provided with an anchoring member of the illustrated type, a suitable hole may be formed by boring two auger holes of a diameter slightly greater than the width of the anchoring member and placing them a distance apart such that upon removing the earth from between the two holes, the length of the completed hole is slightly greater than the length of the elongated anchoring plate, all as shown in Figures 1 and 3. A suitable hole having once been provided the post 10, with the plate 12 attached thereto, is lowered into the hole until the plate comes to rest upon the earth at the bottom, as shown in Figure 2, whereupon the post is rotated a quarter of a turn in either direction to cause the opposite ends of the plate 12, which project laterally beyond the sides of the post 10, to cut or force their way into the solid undisturbed earth that is located at the sides of the hole adjacent to the bottom thereof.

The position that the anchoring plate occupies when a post has been rotated in the

manner described, is well brought out in Figures 3 and 4, from an inspection of which it will be observed that the plate 12 is of rectangular form having the corners uniformly cut away and that the post 10 is connected to the center of the plate. The purpose of truncating the corners of the plate is to enable the anchoring device to slice or shear its way into the soil upon rotation of the post rather than to push or thrust its way in as it would do if the side edges of the plate were allowed to remain straight and unbroken. It will also be noticed that the plate 12 is symmetrically shaped with relation to its longitudinal center line, and this feature of construction insures equal pressure being exerted upon the diagonally opposite edges of the plate as they are cutting into the earth and prevents accidental dislocation of the fence post as it is being rotated. It is to be understood, of course, that the shape of the anchoring plate 12 may be varied as desired without departing from the scope or spirit of the invention. Thus its surface contour may be varied from concave to convex, and its edge contour or profile may be varied in any desired manner as for example, by making it oval, diamond-shaped, etc.; the important consideration being that the plate remain elongated in order that it may be inserted into the hole without engaging the side walls thereof and afterwards operated to anchor itself firmly in the side walls.

In the illustrated embodiment of the invention, the post 10 is shown as equipped with a cross-grip anchor 16 in the form of a plate that is bored out centrally at 18, loosely to encircle the post while resting upon the upper surface of the rigid anchor plate 12. The loose cross-grip anchor does not interfere in any wise with the positive operation of the rigid anchor 12 and increases materially the holding power of the anchor by reason of the fact that the effective area engaged by the earth is approximately doubled. It may be desirable to omit the loose cross-grip anchor from the assemblage, but when posts are being erected in soft or loose soil, it will be found desirable to provide the additional member which, as above pointed out, increases the holding area without necessitating additional labor or other changes of any kind.

The anchoring plate 12 may be advantageously used as a brace plate for corner fence posts and the like and a plate employed in this manner is designated by the reference character 20 in Figure 5. As shown in this view, a brace member 22 is loosely pivoted at 24 to the post 10 and the plate 20 is rigidly mounted upon the free end of the brace member.

In operation, the post 10 is inserted into the hole and the brace member 22 may thereafter be utilized in rotating the post to anchor

the plate 12 in the sides and bottom of the hole. When the post is turned the proper distance and the post hole is back-filled and firmly tamped, the brace 22 is lowered until the brace plate 20 rests upon the ground from which position it is driven to a desired depth in the earth by means of a sledge, or other suitable tool; the only excavating necessary being under the portion of the brace which is driven below the surface.

While the invention has been described herein with particular reference to fence posts, it is to be understood that the invention contemplates employment in connection with other similar poles and posts, and that it contemplates changing the shape and design of the various parts in order to meet conditions prevailing in the vicinity in which the anchoring devices are employed.

Having thus described the invention, what I claim as new and desire to secure by Letters Patent of the United States is:

The combination with a fence post, of an anchoring device associated with the base of the post, said anchoring device comprising two members, one of said members comprising an elongated plate rigidly secured to the base of the post and adapted to be imbedded in the soil upon rotation of the post, the other member comprising a second plate provided with an opening and arranged to loosely encircle the post and to rest upon the upper surface of the first named plate.

Signed at Duluth, Minnesota, this 13th day of September, 1928.

ARTHUR L. GOLDENSTAR.
